[57] **CLAIM**

The ornamental design for an eyeglasses holder, as shown and described.

DESCRIPTION

FIG. 1 is a top, front perspective view of the eyeglasses holder showing my new design;

FIG. 2 is a bottom, rear perspective view thereof;

FIG. 3 is a front elevational view thereof;

FIG. 4 is a side elevational view thereof;

FIG. 5 is a rear elevational view thereof;

FIG. 6 is a top plan view thereof;

FIG. 7 is an enlarged, fragmentary cross-sectional view thereof, taken along the line 7—7 in FIG. 6; and

FIG. 8 is a reduced perspective view thereof showing a pair of eyeglasses in broken lines for illustrative purposes only.

FIG. 1

FIG. 2

FIG. 3

FIG. 4

FIG. 5

FIG. 6

FIG. 8

FIG. 7
